UNITED STATES PATENT OFFICE.

ROBERT GROSSMANN, OF SYRACUSE, NEW YORK, ASSIGNOR TO THE WILL & BAUMER CANDLE COMPANY, OF SYRACUSE, NEW YORK, A CORPORATION OF NEW YORK.

CANDLE-MAKING MACHINE.

1,423,608.

Specification of Letters Patent. Patented July 25, 1922.

Application filed April 13, 1922. Serial No. 552,200.

To all whom it may concern:

- Be it known that I, ROBERT GROSSMANN, a subject of the German Republic, of Syracuse, in the county of Onondaga, in the State of New York, have invented new and useful Improvements in Candle-Making Machines, of which the following, taken in connection with the accompanying drawings, is a full, clear, and exact description.
- 10 This invention relates to the manufacture of what is commonly known as hand-made candles and refers more particularly to a machine for cutting and finishing the candles to the required size, form and color.
- 15 The main object is to provide a simple, compact and efficient machine of this character whereby the operations of cutting, forming and coloring may be performed upon a relatively large number of candles at one and the same time without removing them from the machine.
- 20 Other objects and uses relating to specific parts of the machine will be brought out in the following description.

25 In the drawings:

- Figures 1 and 2 are, respectively, a front elevation and a side elevation of a machine embodying the various features of my invention.
- 30 Figures 3 and 4 are, respectively, a horizontal sectional view taken on line 3—3 Figure 2 and an enlarged vertical sectional view taken on line 4—4, Figure 3.
- 35 Figure 5 is an enlarged top plan of a portion of the system of cutters and underlying support therefor.

- Figures 6 and 7 are, respectively, longitudinal and transverse sectional views taken on lines 6—6 and 7—7 Figure 5.
- 40 Figure 8 is an enlarged horizontal sectional view through one side of the machine taken on line 8—8, Figure 2.

- Figure 9 is an inner face view partly in section of the mechanism shown in Figure 8.
- 45 Figure 10 is a detail sectional view taken on line 10—10 Figure 8.

- Figure 11 is a transverse vertical sectional view partly broken away taken on line 11—11 Figure 2.
- 50 As illustrated, this machine comprises a main supporting frame —1— adapted to rest upon the floor or other suitable sup-

port and provided with upright standards —2— secured to and rising some distance above the ends of the frame —1— near the longitudinal center thereof to form guides for a vertically movable super-structure presently described.

The main frame may be of any suitable construction or material but is preferably rectangular in top plan and provided with corner posts or legs —3—, upper and lower intermediate cross-bars —4—, —5— and —6— connecting the legs at one end and additional brace bars —7— and —8— connecting the front and rear legs, the bars —4— and —7— being disposed in substantially the same horizontal plane and forming the top of the main supporting frame.

The upright standards —2— preferably consist of angle irons —9— arranged in pairs, one pair at each end of the machine, those of each pair being rigidly secured by bolts or equivalent fastening means to the intermediate portions of the cross-bars —4—, —5— and —6— to form a unitary part of the main supporting frame, said bars being disposed in substantially the same longitudinal vertical plane and have their upper ends connected by additional angle irons —10— riveted or otherwise secured thereto lengthwise of the machine and together with the upright angle irons —9— are disposed in transverse spaced relation to receive certain parts of the operating mechanism for the vertical reciprocating unit hereinafter described.

Candle carrier.

A carriage —11— is reciprocally movable vertically along and upon the upright guides or standards —2— between the top of the main frame —1— and upper brace bar —10— and comprises a pair of cross-heads —12— rigidly secured to the opposite ends of a central lengthwise angle bar —13— and supporting a pair of transversely extending angle bars —14— which are rigidly secured thereto and extend forwardly and rearwardly over the opposite ends of the top of the frame —1— just inside of the uprights —2—, said cross-heads being elongated vertically and slidably engaged with the inner faces of the upright bars

—9— and are provided with ribs —15— Figure 8 projecting between and in sliding engagement with the adjacent faces of said bars to hold the cross-heads in an upright 5 position without interfering with their free vertical sliding movement.

These cross-bars —14— are disposed in substantially the same horizontal plane some distance below that of the lengthwise bar 10 —13— and are provided at their ends with journal bearings —16— for receiving and supporting the opposite ends of a pair of cam shafts —17— having eccentric reduced ends —18— journal in said bearings and also 15 provided at one end with hand-wheels —19— by which the cam shafts may be turned independently of each other.

These cam shafts extend forwardly and rearwardly across and to opposite sides of 20 the upright guides or standards —2— in close proximity to their supporting bars —14— to form supporting-guides for the opposite ends of a candle carrying supporting-plate —20— of wood or other suitable material having a plurality of, in this instance 25 four, lengthwise rows of hooks —21— in parallel transversely spaced relation and also in longitudinally spaced relation to form a plurality of, in this instance twelve, trans- 30 verse rows, said hooks being preferably secured to the under side of the candle-supporting plate —20— for receiving a corresponding number of pendent candles —a— through the medium of their wicks —a'— 35 Figures 1 and 2 preparatory to cutting and finishing said candles in a manner herein-after described.

The plate —20— with the previously 40 formed candles attached thereto is brought to the machine and placed with their ends loosely resting upon the cam shafts —17— which by reason of their eccentrically journaled end spindles —18— permit either end of the plate —20— to be adjusted a limited 45 distance vertically to bring the several candles into proper alignment with their respective cutters and finishing dies hereinafter more fully described, the transverse width of the candle-supporting plate being somewhat 50 less than half the length of the cross-bars —14— so that it may be supported wholly at the front or at the rear of the standards —2— and is slidable along and upon said cam shafts beneath the lengthwise bar —13— from one 55 position to the other or from a position directly over the cutters to a position directly over the finishing dies.

A pair of alining bars —22— extends lengthwise of and upon the lower horizontal 60 flanges of the transverse bars —14— from end to end thereof and are pivoted at —23— thereto to swing in horizontal planes, the other ends being provided with handles —24— by which they may be operated. The inner 65 edges of the intermediate portions of these

alining bars are provided with notches —25— arranged in uniformly spaced relation corresponding to the required spacing of the lengthwise rows of candles —a— on the board or plate —20— and are located in a 70 horizontal plane just below the hooks —21— when the ends of the board —20— are resting upon the cam shafts —17— and serve to engage the adjacent wicks —a'— and thereby to permit the board —20— to be properly 75 positioned on the cam shafts forwardly and rearwardly for registering the candles with the underlying cutters and finishing dies.

In other words, these alining bars —22— may be used in conjunction with the cam 80 shafts —17— for properly positioning the board to cause its candles to be properly aligned first with the cutters and sequentially with the finishing dies as the carriage is lowered from its normal up position as shown in 85 Figures 1 and 2.

A lengthwise rock shaft —26— is loosely mounted at its ends in guide slots —27— on the cross-heads —12— and is provided intermediate its ends with a pair of radial arms 90 —28— projecting in the same direction from one side of the shaft for receiving and supporting a gage bar —29— which is rigidly secured to the free ends of said arms parallel with said rock shaft and extending from 95 end to end of the machine between the cross-heads —12—.

This rock shaft —26— and its radial arms —28— together with the gage bar —29— are normally disposed in a horizontal plane between the lengthwise carriage bar —13— and cam shafts —17— in which position, the opposite ends of the rock shaft —26— rest in the lower end of the slots —27—, the spacing of the arms —28— and length of the bar —29— being adjusted to enable them to swing vertically between the cam shafts —17— without friction therewith. One end of the rock shaft —26— extends longitudinally beyond the corresponding standard 105 —2— and is provided with a crank arm —30— to which is fastened a cable —31— carrying a weight —32— by which the rock shaft and gage bar —29— are held in their 110 normal positions.

Secured to the rock shaft near the crank arm —31— is a cam —33— which is adapted to engage a stop pin —34— on the adjacent upright —2— when the carriage approaches the limit of its downward movement for 115 locking said shaft against the action of the counter weight —32— and thereby swinging the gage bar —29— downwardly from its normal horizontal position to a substantially vertical position directly under the shaft 120 —26— to be used as a sight gage extending across the longitudinal rows of candles to determine the length at which the candles are to be cut, the gage bar —29— being adjusted so as to register approximately with 125 130

the upper ends of the body of their candles at the junction of their wicks when swung downwardly to a substantially vertical position by the engagement of the cams —33— 5 with the pins —34—.

These pins —34— are adjustable in different holes —35— in the uprights —2— for varying the lengths at which the candles are to be cut or rather for varying 10 the period of downward movement of the gage bar —29— during the descent of the carriage to the cutters and thereby to vary the length of the candles so that those which are cut in each operation may be of 15 the same length. That is, if the candles are to be cut to greater length, the pins —34— will be adjusted to superposed holes —35— while on the other hand, if they are to be shortened, the pins will be adjusted to the 20 underlying holes.

Carriage operating means.

The means for moving the carriage vertically consists, in this instance of a horizontal shaft —36— journaled in suitable bearings —37— at the under side of the top of the main frame —1— and provided at its outer end with a hand-wheel —38— and at its inner end with a drum —39— around 25 which is wound a cable —40— having one end passed over a sheave —41— and attached to a weight —42— and its other end passed under a separate sheave —43— and thence upwardly over a pair of sheaves —44— on the brace bar —10— and thence downwardly where it is attached to the lengthwise bar —13— of the carriage.

The weight —42— serves to counter balance the weight of the carriage and candle 40 supported thereby while the hand-wheel —38— serves as a means for operating and controlling the vertical movement of the carriage through the medium of the cable.

Candle-cutting device.

A substantially flat metal plate —45— is secured in a horizontal position to the top of the main frame —1— to extend from end to end thereof at one side of the uprights 50 —2— and is provided with a series of downwardly tapered openings —46— therethrough corresponding in number to the number of candles which may be supported upon the plate —20— and in vertical alinement therewith when the latter are properly adjusted on the carriage.

These openings —46— are of sufficient size to permit the lower larger ends of the unfinished candles to readily pass therethrough when the carriage with the candles thereon is lowered, said openings being 60 arranged in a series of, in this instance four, lengthwise rows with a series of, in this instance twelve, holes to a row, the 65 lengthwise rows being arranged in parallel

spaced relation while the transverse rows are also arranged in parallel spaced relation, the positions corresponding to those of the candles when the latter are properly suspended on the carriage.

A series of, in this instance twelve, shearing blades —48— are secured by screws —49— in suitable recesses in the upper face of the plate —45— at one and the same side of each transverse row of openings —46— 70 and each plate is provided with a series of semi-circular cutting edges —50— registering with and forming the corresponding sides of the main candle openings of the corresponding lengthwise rows.

A series of, in this instance four, cutting blades —51— are movable longitudinally across and upon the upper face of the plate —45— in guide ways —52— and are provided with lengthwise rows of openings 75 —53— movable into and out of registration with the openings 46, said blades being provided with cutting edges —54— at corresponding sides of their openings —53— to cooperate with the cutting edges —50— 80 of the fixed blades —48— for shearing or cutting off the lower ends of the candles which may project into the openings —46— when the candle carriage is lowered.

The several shearing blades 51 are connected at one end by a yoke bar —55— which in turn is connected by a link —56— to one end of an operating lever —57—, the latter being fulcrumed or pivoted at —58— to the upper face of the plate —55— near 90 one end thereof and is provided with a handle —59— by which it may be operated to reciprocate the several blades —51— simultaneously to and from their cutting positions.

Candle base finishing.

Suitable means is provided for producing a tapered finished to the ends of the candles as they have been cut to the desired length 110 and for this purpose is provided a hollow die-supporting member —60— adapted to be heated from any suitable source of heating supply and is preferably square in cross section and provided on each face with a set of dies —61— corresponding in number and position to the number and position of the candles on the plate —20— when the latter with the candles thereon cut to the required length is shifted to the position directly over 115 the heated die carrier —60—, the dies of each set being provided with tapering sockets —62— for receiving and finishing base ends of the candles as they are lowered into the dies by the downward movement of the 120 carriage —11—.

The sockets —62— of each set of dies are of slightly different diameters for producing corresponding tapers of the candles, which may be engaged therein.

115

120

125

- The carriage —60— is provided with co-
axial and trunnions —63— journaled in suit-
able bearings —64— on the main frame
—1— at the side of the uprights —2— oppo-
site that of the cutter-supporting plate
—45— whereby the die carrier may be ro-
tated to present either set of dies at the top
for receiving the lower ends of the candle
when the carriage is lowered, one at least of
10 the trunnions being hollow for connection
with a source of steam supply or other heat-
ing agent whereby the dies —61— may be
kept in a heated condition when the ma-
chine is in use.
- 15 The bases of the several dies —62— are
bolted or otherwise secured to the corre-
sponding sides of the carrier —60— and are
provided with radial channels or outlets
—65— to permit any excess melted candle
20 material to escape therethrough into regis-
tering channels —66— in the adjacent sur-
face of the carrier, thereby permitting a
smooth finish of the bottom of the candles.
- 25 The upper ends of the sockets —62— of
the several dies are also provided with lat-
eral passages —67— to permit the escape of
any excess melted candle material while the
bases of the candles are being molded in the
dies.
- 30 In some instances, the candles are colored
by dipping them into a vat containing the
coloring matter and for this purpose, I have
provided the frame —1— with an extension
—1'— constituting a track upon which is
35 mounted a vat —B— containing a coloring
matter and provided with wheels —b— move-
able along the track to and from a position
directly over the die carrier —60— and of
sufficient interior dimensions to receive the
40 entire series of candles, which may be sus-
pended from the supporting board or plate
—20— as the latter have been cut to the de-
sired length and their lower ends tapered
to the desired finish.
- 45 *Operation.*
- The uncut candles which have been pre-
viously formed by repeated dipping in the
molten wax or other material are brought
50 to the cutting and finishing machine sus-
pended from the supporting plate —20—
which is placed by hand upon the cam shafts
—17— on the carriage —11— so as to aline
vertically with their respective openings in
55 the cutting table —45—, this alinement be-
ing affected by proper adjustment of the cam
shafts —17— and alining bar —22—, it be-
ing understood that during this operation,
the carriage —11— is in its extreme up po-
60 sition as shown in Figures 1 and 2.
- The carriage with the uncut candles sus-
pended from the plate —20— is then low-
ered by means of a hand-wheel —38— and
cable —40— until the cams —33— engage
65 the stop pins —34— in the proper holes
- 35— to rock the gage bar —29— down-
wardly to the proper position for cit-
ing across the upper ends of the candles where-
upon if the upper ends of the candles are
not in exact alinement with the gage bar, the
70 ends of the candle-supporting board may be
adjusted up or down as required by means
of the cam shafts —17— to affect the de-
sired alinement at which time, the lower
ends of the candles will have entered their
75 corresponding openings in the cutting board
—45—.
- The cutting blades —51— are then oper-
ated by means of the hand-lever —57— to
sever the lower ends of the candles from the
80 main body, thereby cutting them all the
same length, the severed portions falling
through the openings —46—.
- Immediately following this cutting opera-
tion, the carriage with the cut candles
85 thereon is then raised and the candle-sup-
porting board —20— is moved along the
cam shafts —17— to a position directly
over the die carrier —60— and again ad-
justed by means of the cam shafts to prop-
erly aline the candles with the uppermost
90 set of dies.
- The carriage with the cut candles thereon
is then lowered to cause the lower ends of
95 the candles to enter the tapering sockets in
the several underlying dies which being
heated instantly melt the contacting por-
tions of the candles and produce the desired
tapered thereon, the surplus wax or other
100 candle material readily flowing off through
the passages —65— and —67— leaving the
ends of the candles smooth while their ex-
treme lower faces are flattened by contact
with the bottoms of the sockets or adjacent
105 portions of the heated carrier.
- After this taper finishing operation, the
carriage with the candles thereon is again
raised and if it is desired to color the candles,
the vat —B— containing the coloring mat-
ter may be moved to a position beneath the
110 candles or directly over the die carrier
—60— whereupon the carriage may be low-
ered to dip the candles in the coloring mat-
ter in the vat, the carriage being then raised
and the vat —B— withdrawn from beneath
115 the same while the board with the finished
candles thereon may then be removed to per-
mit a repetition of the operations previously
described.
- What I claim is:
1. In a candle making machine, the com-
bination of a candle cutting device having
a multiplicity of cutters, a candle carrier
having means for supporting a multiplicity
of candles in alinement with the cutters,
means for operating the carrier to bring
125 the candles into position to be cut by the
cutting device, and means for operating the
cutters into cutting engagement with the
candles.

2. In a candle cutting and finishing machine, a cutter-supporting plate having openings therein for receiving one end of the candles, a candle-supporting carriage movable toward and from said plate to cause the candles to enter the openings therein, and a cutter for severing said ends of the candles while in the openings.
3. In a candle cutting and finishing machine, the combination of a horizontal shearing plate having a multiplicity of openings, a vertically movable carriage, means on the carriage for suspending a multiplicity of candles in vertical alinement with the openings, means for raising and lowering the carriage to cause the lower ends of the candles to move into and out of the openings in the shearing plate, and a cutter cooperating with the shearing plate for severing the lower ends of the candles while in the openings.
4. In a candle cutting and finishing machine, the combination of a horizontal shearing plate having a multiplicity of openings, a vertically movable carriage, means on the carriage for suspending a multiplicity of candles in vertical alinement with the openings, means for raising and lowering the carriage to cause the lower ends of the candles to move into and out of the openings in the shearing plate, a cutter cooperating with the shearing plate for severing the lower ends of the candles while in the openings, and means on the carriage for adjusting the candle-supporting means vertically.
5. In a candle-cutting and finishing machine, the combination of a horizontal shearing plate having a multiplicity of openings, a vertically movable carriage, means on the carriage for suspending a multiplicity of candles in vertical alinement with the openings, means for raising and lowering the carriage to cause the lower ends of the candles to move into and out of the openings in the shearing plate, a cutter cooperating with the shearing plate for severing the lower ends of the candles while in the openings, and means on the carriage for engaging certain of the candle wicks to enable the supporting means to be properly adjusted for alining the candles with their respective openings in the cutter plate.
6. In a machine for cutting and finishing candles, the combination of a horizontal cutter-supporting plate having a multiplicity of openings arranged in lengthwise and transverse rows, a carriage movable vertically toward and from said plate, means on the carriage for suspending a multiplicity of candles in vertical alinement with said openings, said means including a candle-supporting board and vertically adjustable rests therefor, and cutters on said plate cooperating therewith for severing the lower ends of the candles when the latter are lowered into the openings.
7. In a candle cutting and finishing machine, the combination of a cutting device having a multiplicity of vertical openings, a carriage movable vertically toward and from said cutting device, means on the carriage for suspending a multiplicity of candles in vertical alinement with said openings whereby the lowering of the carriage will cause the lower ends of the candles to enter the openings, and means for operating the cutting device to sever the ends of the candles in the openings.
8. In a candle cutting and finishing machine, the combination of a cutting device having a multiplicity of vertical openings, a carriage movable vertically toward and from said cutting device, means on the carriage for suspending a multiplicity of candles in vertical alinement with said openings whereby the lowering of the carriage will cause the lower ends of the candles to enter the openings, means for operating the cutting device to sever the ends of the candles in the openings, and a horizontal gage bar adjustable vertically relatively to the carriage to determine the lowering movement of the candles into the openings of the cutting device and thereby to determine the length of the cut candles.
9. In a machine for finishing candles, the combination of a die carrier having a multiplicity of vertical heated sockets, a carriage movable vertically toward and from the die carrier, and means on the carriage for suspending a multiplicity of candles in vertical alinement with said sockets whereby the downward movement of the carriage will cause the lower ends of the candles to engage in said sockets for finishing purposes.
10. In a candle finishing machine, a die carrier having a multiplicity of sockets actively disposed in a vertical position, a carriage movable vertically toward and from the die carrier, adjustable means on the carriage for suspending a multiplicity of candles in vertical alinement with said sockets to cause their lower ends to enter the sockets when the carriage is lowered, and means for heating the sockets.
11. In a candle finishing machine, a die carrier having a multiplicity of sockets actively disposed in a vertical position, a carriage movable vertically toward and from the die carrier, adjustable means on the carriage for suspending a multiplicity of candles in vertical alinement with said sockets to cause their lower ends to enter the sockets when the carriage is lowered, and means for heating the sockets, said sockets having drainage channels at their bases to remove the molten candle material therefrom.
12. In a candle finishing machine, a die carrier having a multiplicity of sockets ac-

tively disposed in a vertical position, a carriage movable vertically toward and from the die carrier, adjustable means on the carriage for suspending a multiplicity of candle pins in vertical alinement with said sockets to cause their lower ends to enter the sockets when the carriage is lowered, and means for heating the sockets, said sockets having drainage openings near the upper ends

thereof to permit the escape of molten candle material therefrom.

In witness whereof I have hereunto set my hand this 10th day of April 1922.

ROBERT GROSSMANN.
